UNITED STATES PATENT OFFICE.

JOSEPH W. PARKS, OF ALTOONA, PENNSYLVANIA.

TIPPING HAND TOOL.

1,418,394.

Specification of Letters Patent. Patented June 6, 1922.

Application filed January 27, 1921. Serial No. 440,535.

To all whom it may concern:

Be it known that I, JOSEPH W. PARKS, a citizen of the United States, residing at Altoona, in the county of Blair and State of Pennsylvania, have invented certain new and useful Improvements in Tipping Hand Tools, of which the following is a specification.

This invention relates to shoe laces and has for its primary object improved means for providing shoe lace ends with stiffening tips and has particular reference to hand-operated tools for firmly fastening the shoe tip around the lacing.

Another object of this invention is to provide a tool having a minimum number of parts, each coacting so as to firmly grip the tip around the lacing, and to consist of parts that are easily constructed and manufactured and sold at a cost that is readily within the reach of any householder.

A still further object of this invention is to provide a simple, inexpensive shoe lace tip fastening device for home use, wherein the lace end stiffening tips can be easily applied, which quite frequently pull off, or in cases where shoe strings are found too long, the string can be cut and retipped or the broken ends of old strings can be likewise tipped and made to render additional service to the wearer.

With these and many other objects in view which will be more readily apparent as the nature of the invention is further understood, the same consists in the novel construction combination and arrangement of parts as will be herein fully pointed out, illustrated and claimed.

It will be readily understood by those skilled in the art to which this invention belongs that the same is susceptible to some structural change or modification without departing from the spirit or scope of the invention, but a preferred and practical embodiment of the invention is shown in the accompanying drawings in which:

Fig. 1 is a plan view of my improved tool for firmly attaching shoe lace tip to shoe laces and shows a lace in position after the tip has been attached thereto.

Fig. 2 is a side elevation of the parts shown in Figure 1.

Fig. 3 is a sectional view taken on the line 3-3 of Figure 2 and shows the die and die plunger in operative relation with a shoe lace tip in position.

Fig. 4 is an enlarged view of the die and plunger together with the shoe lace tip partly formed around the shoe lace.

Fig. 5 shows successive steps through which the shoe lace tip passes when being securely attached to the shoe lace.

Fig. 6 shows the metal tip after it has been attached to the shoe lace and shows the manner in which the lace is compressed where the tip is attached.

Like reference numerals refer to similar parts throughout the several figures of the drawings.

In the manufacture of this improved tool, I make two lever members designated by the numerals 10 and 11, and to the member 10, I pivotally attach a plunger, 12. The lever members 10 and 11 are pivotally connected at 13 by a rivet or similar means, 14.

The lever members are normally held apart by outwardly extending lugs 15 made as an integral part of the plunger 12, engaging the sides 16 of the lever member 11, which also acts as a stop to insure the proper compression of the metal tip for the die.

The female portion or seat of the die in which the metal tip 17 is formed is constructed as an integral and intermediate part of the lever member 11 and to this end the lever elements 10 and 11 are both preferably made in dies from blanks properly cut out for the purpose intended. In the formation of the lever element 11, the sides 18 of the portion forming the die for shaping the metal tip 17 on the lace 19, are drawn together sufficiently to permit the male portion of the die or plunger 12 to snugly fit therebetween.

This construction in addition to forming the die as above explained facilitated the pivotal assembly of the parts 10 and 11 as shown in Figure 2 of the drawings. The element 11 is bifurcated at the pivotal end for the purpose of permitting the introduction of the shoe lace end into the die designated in its entirety by the numeral 20.

The male portion or plunger 12 of the die is pivotally connected with the lever element 10 by a rivet or bolt 21, which is adapted to pass through the sides 22 and hold the die plunger 12 in a sandwiched position in direct operating alignment with the female portion of the die which is made as an integral part of the operating element 11.

In order that the metal tip may present a substantially tubular shape after it is ap-

plied to the end of the lace 19 the plunger 12 is provided with a plurality of lugs 15 which engage the sides 16 of the member 11 as shown in detail in Figure 4. These lugs 5 serve to restrict the pressure on the tip after the same has been properly formed.

In order that the die plunger 12 may not impinge on the edges 23 of the metal tip blank during the process of forming the 10 tip around the shoe lace, the face is made concave with pendant edges engaging the sides of the female portion of the die. This construction permits the forming of the tip without crushing the blank as would be the 15 case if the plunger impinged upon the sides 23 of the blank.

The tip blanks are preferably provided with perforations having inwardly extending 20 tongues or projections which engage the threads of the lace and assist materially in keeping the tip in place.

When using this improved tool the plunger 12, is withdrawn from the die sufficiently to allow the blank 17 to be placed in the 25 die 20 after which the shoe lace is placed in the blank the plunger 12 is then brought down on the blank, at first the edges 24 are slightly turned in after which one edge will 30 overlap the other and a slight rolling action takes place when the metal blank is rolled around the end of the lace and pressed down 35 tight upon it, as shown in Figure 6 of the drawings. The only effort necessary is a slight pressure on each of the lever elements.

For the purpose of keeping the lever elements at a distance apart sufficient to readily insert the blank and the lace end a helical spring could be readily interposed on the line 5—5 of the Figure 1, but this extra

cost was not thought justifiable for a tool 40 of this kind that is designed to sell at small cost.

I claim:

1. A shoe-string tipping tool of the class described, including a pair of lever members 45 connected at one end, a tip forming seat formed between the ends of one of said members and a die plunger carried by the intermediate portion of the other member and having a die face complementary to said 50 seat.

2. A shoe-string tipping tool of the class described including a pair of lever members pivotally connected at one end and one of 55 said members having a slot adjacent the pivot and a seat communicating with said slot to receive the shoe-string and tip blank, and a tipping die carried by the opposite member for co-operating with the said seat.

3. In combination with a hand tool for 60 applying tip to shoe laces, lever members, a die member made integral with a lever member, a bifurcated end for the die member, means for applying the lace end in the blank and means for wrapping and compressing the metal tip around the lace end. 65

4. A shoe-string tipping tool of the class described including a pair of lever members of channel cross section pivotally connected at one end, and a tipping die carried by one 70 of said members and co-operating with the channel portion of the opposite member to clinch a tip blank placed therein about the end of a shoe-string.

In testimony whereof I affix my signature. 75

JOSEPH W. PARKS.
